SPRING ACTUATED TOP

Franklin H. Gustine, Chicago, Ill.

Application December 5, 1950, Serial No. 199,233

2 Claims. (Cl. 46—69)

1

The present invention relates to improvements in twin tops and has for an object certain improvements on U. S. Patent No. 1,985,657 granted December 25, 1934, to Franklin J. Gustine and entitled Spring Operated Mechanical Toy.

Another object of the present invention is to provide an improved toy of this character in which a housing is provided for supporting and embracing the operating spring.

A further object of the present invention is to provide an improved structure in which the spindle of the lower top is resiliently supported by the operating spring which is placed under torsional tension only by the winding operation so that less force is required to break the interlock between the two tops at the time of launching or dropping the tops to effect the individual spinning thereof.

A still further object of the present invention is the provision of twin tops which comprise relatively few parts, are economical to manufacture and are sturdy so that they will stand the rough usage to which they will be put.

With the foregoing and other objects in view, the invention will be hereinafter more fully described and more particularly pointed out in the appended claims.

In the drawings, in which the same parts are denoted by the same reference numerals throughout the several views,

Figure 1 is a perspective view of the improved device at the moment the interlock is broken between the upper and the lower tops,

Figure 2 is a fragmentary perspective view of the lower top and the spindle of the upper top at the beginning of the winding operation,

Figure 3 is a view similar to that of Figure 2 but at the completion of the winding operation,

Figure 4 is a fragmentary exploded perspective view of the lower top showing the ratchet sleeve, the spindle, the septum and the volute spring,

Figure 5 is a vertical sectional view of the twin tops in assembled relation ready for the winding operation,

Figure 6 is a sectional view taken on the line 6—6 of Figure 5 and looking in the direction of the arrows, and

Figure 7 is a sectional view taken on the line 7—7 of Figure 4 and looking in the direction of the arrows.

Referring more particularly to the drawings, the improved toy comprises twin tops generally designated as an upper top 10 and a lower top 11. The upper top 10 comprises a pair of dish shaped or concavo-convex sections 12 and 13

which are joined together at their marginal edges by an overturned seam 14 to provide a hollow body and a spindle 15 extending through aligned substantially centrally positioned openings in the sections 12 and 13. The spindle is fixedly secured to the sections 12 and 13 in any suitable manner and projects above and below the sections and its lower end portion has a tapered blunt end 16 upon which the upper top 10 is adapted to spin when deposited or launched upon a flat surface. The spindle 15 is provided in spaced relation to its lower end 16 with a laterally or radially extending pin 17 to provide a winding key and a locking pawl for cooperation with the lower top as later described.

The lower top 11 comprises an upper section 18 and a lower section 19 which are similar in shape and construction to the upper top sections 12 and 13, respectively, and provide a hollow body. The sections 18 and 19 have marginal edge flanges 20 and 21, respectively, between which are positioned the peripheral edge portion of a septum 22 which is positioned within the hollow body formed by the sections 18 and 19. The sections 18 and 19 and the septum 22 are held in assembled relation by a flange which has a vertical portion 23 extending downwardly from the flange 20 of the section 18 across the edges of the septum and the flange 21 of the section 19 and a horizontal portion 24 firmly engaging the under face of the flange 21.

The septum 22 has an enlarged substantially centrally disposed opening 25 therein and depending from the wall of the opening 25 is a skirt or flange 26 the lower edge of which rests upon the inner face of the section 19 and in cooperation therewith forms a housing and a support for a volute spring 27. The outer end portion of the spring 27 extends through a slit 28 formed in the skirt 26 and is bent upon itself to form a hook 29 which faces in the direction of the movement of the spring during the winding or coiling operation.

The hook 29 receives the opposed adjacent wall 30 of the slit 28 and the other wall of the slit 28 is bent inwardly as at 31 and due to its inherent resiliency the bent portion 31 will tend to return to its original position and will frictionally engage the spring 27 adjacent the hook 29 to urge the closed portion of the hook towards the wall 30.

The inner end portion of the spring 27 extends through a slot 32 formed in a hollow spindle 33 at substantially the longitudinal center thereof. The spindle extends through aligned substantially

centrally disposed openings in the sections 18 and 19 of the lower top 11 and through the opening 25 of the septum and the innermost convolution of the spring 27. The inner end portion of the spring which is disposed within the hollow spindle 33 is bent as at 34 to prevent the escape of the inner end portion of the spring from the spindle.

The spindle 33 extends above and below the sections 18 and 19 and has a tapered blunt closed lower end 35 upon which the lower top may spin and its upper end is open as indicated at 36 and has a shoulder 37 formed by a cam surface 38 in the upper edge of the spindle 33. A ratchet or locking sleeve 39 is fixed in any suitable manner in the opening in the upper section 18 of the lower top 11 and encircles the upper portion of the spindle 33 to provide a bearing for the upper end of the spindle. The upper end portion of the sleeve 39 projects above the action 18 and the upper edge of the sleeve has a pair of diametrically disposed shoulders 40 and 41 which are formed by the cam surfaces 42 on the upper edge of the sleeve. The shoulders 40 and 41 face in a direction opposite to that in which the shoulder 37 of the spindle 33 faces, that is the shoulders 40 and 41 face in a clockwise direction and the shoulder 37 faces in a counterclockwise direction.

In the use of the improved toy the lower end portion of the spindle 15 of the upper top 10 will be inserted into the open upper end 36 of the spindle 33 of the lower top 11. The lower top will be grasped in one hand and the upper top will be grasped in the other hand. The two tops will then be turned relatively to a position to engage the pin 17 of the upper spindle 15 with the shoulder 37 of the lower spindle 33 so that the lower spindle will be turned in the lower top during the winding action.

At the same time the upper top is depressed toward the lower top so as to bring the pin 17 in front of one of the shoulders 40 or 41 of the sleeve 39 to prevent the spindle 33 turning backward while a new grip is secured upon the tops for further winding action. As further rotative action is imparted to the tops the pin 17 will ride up one of the cam surfaces 42 to reach the forward face of the shoulder 40 or 41. Since the rotative action of the tops places the spring 27 under torsional strain the spring will maintain the shoulder 37 in interlocking engagement with the pin 17 and the fact that the spindle 33 is resiliently supported by the spring 27 the spindle 33 will have longitudinal movement in both directions so that the spindle 33 and the pin 17 will be free to move as a unit axially of the spindle 33. When the spring 27 has been wound sufficiently the pin 17 will be forced down into engagement with one of the shoulders 40 or 41 of the sleeve 39 and the torsional pressure of the spring 27 acting through the spindle 33 and the shoulder 37 is sufficient to frictionally hold the pin 17 against the shoulder 40 or 41.

After the tops have been wound together until the desired tension of the spring 27 is obtained, the twin tops may be dropped as a unit so that the point 35 of the lower spindle 33 strikes the floor 43 or other hard supporting surface. The jar thus produced is sufficient, supplemented by the inertia of the lower top body 11, to dislodge the pin 17 from the shoulder 40 or 41 so that the spring 27 not only reacts against the two spindles 15 and 33 to turn them in opposite directions but also acts to eject the upper spindle 15 out of

the open end 36 of the lower spindle 33. During this action the shoulder 37 of the spindle 33 is maintained for a sufficient period of time in pressing contact with the pin 17 so as to rapidly turn the upper spindle 15 with the upper top 10 in a direction opposite to the turning of the spindle 33 and the lower top 11.

The result of this operation is that the tops are turned or spun in opposite directions and the upper top is ejected with sufficient force to throw it to one side of the lower top so that the two tops are left spinning independently upon the floor.

If desired any number of shoulders could be provided on the sleeve 39. The skirt 26 which acts as a housing for the spring 27 will confine the movement of the spring during unwinding operation thereof to help prevent displacement of the spring with respect to its anchorage in the slit 28 of the skirt and in the spindle 33. It will be noted from Figure 5 of the drawings that the lower edge of the spring 27 is spaced above the inner face of the section 19 so that when the spindle 33 is moved downwardly during the winding operation there will be sufficient space between the spring and the section 19 to permit such movement without permitting distortion or displacement of the spring 27.

It is obvious that various changes and modifications may be made in the details of construction and design of the above specifically described embodiment of this invention without departing from the spirit thereof, such changes and modifications being restricted only by the scope of the following claims.

What I claim is:

1. In an improved twin top construction, a hollow top having a concavo-convex lower and upper wall, said walls being provided with lateral flanges at their peripheral edge portions and having their concave faces in confronting relation, a septum transversely mounted between the walls and having its marginal edge portion clamped between the flanges of the upper and lower walls, one of said flanges having a vertical portion terminating in a lateral extension and encompassing the marginal edge portion of the septum and flange of the other wall, said septum having an enlarged center opening, a skirt extending at right angles from the septum and bounding the opening, said skirt being secured to the concave face of one of said walls, said walls having centrally disposed aligned openings, said opening in the septum being concentric to said openings, a spindle slidably disposed through said openings in the walls and having an axial slot, said skirt having an axial slit therein, a volute spring disposed within the confines of said skirt and having its outer end portion engaged in the slit in said skirt and its inner end portion anchored in the slot in said spindle.

2. In an improved twin top construction, a hollow top having a concavo-convex lower and upper wall, said walls being provided with lateral flanges at their peripheral edge portions and having their concave faces in confronting relation, a septum transversely mounted between the walls and having its marginal edge portion clamped between the flanges of the upper and lower walls, one of said flanges having a vertical portion terminating in a lateral extension and encompassing the marginal edge portion of the septum and flange of the other wall, said septum having an enlarged center opening, a skirt extending at right angles from the septum and

bounding the opening, said skirt being secured to the concave face of one of said walls, said walls having centrally disposed aligned openings, said opening in the septum being concentric to said openings, a spindle slidably disposed through said openings in the walls and having an axial slot, said skirt having an axial slit therein, a volute spring disposed within the confines of said skirt and having its outer end portion engaged in the slit in said skirt and its inner end portion anchored in the slot in said spindle, said slit being defined by two walls one of which resiliently urges said outer end portion of the spring into frictional binding engagement with the other of said walls of the slit.
